DESIGN FOR AN ORNAMENT FOR A SHOE OR SIMILAR ARTICLE

Jack Kowal, Brooklyn, N. Y.

Application November 28, 1936, Serial No. 66,186

Term of patent 3½ years

To all whom it may concern:

Be it known that I, Jack Kowal, a citizen of the United States of America, residing in Borough of Brooklyn, county of Kings, city and State of New York, have invented a new, original, and ornamental Design for an Ornament for a Shoe or Similar Article, of which the following is a specification, reference being had to the accompanying drawing, forming part thereof,

Fig. 1 is a front view of an ornament for a shoe or similar article showing my new design.

Fig. 2 is a side elevational view of the shoe ornament shown in Fig. 1.

I claim:

The ornamental design for an ornament for a shoe or similar article, substantially as shown.

JACK KOWAL.
